UNITED STATES PATENT OFFICE.

CHARLES S. JONES, OF MARION, INDIANA.

SELF-MEASURING PUMP.

No. 872,943.

Specification of Letters Patent

Patented Dec. 3, 1907.

Application filed November 5, 1906. Serial No. 342,164.

To all whom it may concern:

Be it known that I, CHARLES S. JONES, a citizen of the United States, residing at Marion, county of Grant, State of Indiana, have 5 invented certain new and useful Improvements in Measuring-Pumps, of which the following is a specification.

This invention relates to pumps of that general class in which provision is made for 10 indicating or registering the amount of liquid delivered by the pump from a tank or other receptacle.

One of the principal objects of the invention is to provide a pumping device of very 15 simple construction which may be readily attached to a tank or other container, and which may be accurately adjusted for the purpose of indicating or registering the exact quantity of liquid delivered.

20 A further object of the invention is to provide a device of this class in which the indicating or registering mechanism may be quickly adjusted for the purpose of indicating different quantities delivered, as for instance, pints or quarts or gallons.

A still further object of the invention is to provide an improved means for securing the pump in place within the tank or other oil container.

30 A still further object of the invention is to provide an improved form of delivery nozzle which will prevent waste of the liquid by dripping.

With these and other objects in view, as 35 will more fully hereinafter appear, the invention consists in certain novel features of construction and arrangement of parts, hereinafter fully described, illustrated in the accompanying drawings, and particularly 40 pointed out in the appended claims, it being understood that various changes in the form, proportions, size and minor details of the structure may be made without departing from the spirit or sacrificing any of the advantages of the invention.

In the accompanying drawings:—Figure 1 is an elevation, partly in section, of a measuring pump constructed in accordance with the invention. Fig. 2 is a similar view taken 45 at a right angle to Fig. 1. Fig. 3 is a detail view, partly in section, of the delivery nozzle. Fig. 4 is a plan view of one of the pump supporting frames.

Similar numerals of reference are employed to indicate corresponding parts

throughout the several figures of the drawings.

The frame of the pump comprises a vertically arranged hollow standard 1 provided at its lower end with angularly bent arms 1^a 60 which are pivoted or otherwise secured to a suitable supporting frame.

The pump is arranged for attachment to a tank or other containing vessel, the cap or cover of such tank being indicated at B, and 65 above this cap or cover is a frame A and below is a frame C, the two frames being of similar construction and preferably formed of strap iron.

The supporting frames each include a pair 70 of parallel bars a a' which are connected together by an approximately U-shaped brace b, and at one side of the bar a' is riveted a bar c, the ends of which extend at an obtuse angle to each other, and are arranged to engage 75 against the side walls of the tank. To the rear face of the bar a is secured a bracing bar d which, also, extends outward into engagement with the vertical walls of the tank, or containing vessel. The arms 1' of the main 80 standard or frame extend through the cover and are rigidly secured to both of the frames a—c, and this forms a solid, rigid connection which will hold the pump in place while in operation.

85 Suspended within the tank or containing vessel is a cylinder 21 having upper and lower heads 30 and 29 which are connected together by tie rods 22. In the lower head 29 is an inlet 26 closed by a valve 25 and 90 working within the cylinder is a piston 23 that is carried by a piston rod 5, so that on the up stroke of the piston the valve 25 will be opened to permit the oil or other liquid to flow into the lower end of the cylinder. On 95 the down stroke of the piston, the liquid is forced out through a discharge port 27 which is connected to a vertically arranged discharge pipe 32 by an elbow 28, there being a suitable check valve 31 arranged in the discharge pipe in order to prevent back flow 100 into the cylinder.

The upper portion of the piston rod is mounted in suitable bearings formed in the standard, and to the rod is secured a block 7 105 which may be adjusted with respect to the length of the rod in order to secure accurate operation. Projecting from this block is a pointer arranged to travel over a suitable scale marked on the vertical standard 1, the 110

scale being shown bearing suitable numerals 1, 2, 3 4 and 5 which may be spaced in accordance with the cubic content of the pump cylinder for indicating gallons, quarts or 5 other units of liquid measurement.

The upper portion of the casing or standard 1 is rounded to form a pair of housings, through one of which extends a shaft 2 carrying a handled crank 2'. On this shaft is secured 10 a sprocket wheel 3, over which passes a link belt 4, the belt passing also over an idler 20 near the lower portion of the casing. The handled crank forms the operating means, and by turning the crank first in one 15 direction and then in the other, the piston may be raised to permit the filling of the cylinder to any desired extent, and then forced down for the purpose of discharging a portion or all of the contents of the cylinder as 20 may be required, the extent of the movement and the quantity of liquid delivered being indicated on the scale.

In the second of the housings at the upper portion of the casing is mounted a shaft 2^a 25 on which is secured a ratchet wheel 17, and with this ratchet wheel engages a pawl 14, said pawl having a stop shoulder 16 which is normally drawn into engagement with the upper wall of the casing by a retractile spring 30 15, the shoulder projecting beyond the wall of the casing for a purpose hereinafter described. At one end of the shaft is secured a pointer 18 which is arranged to move over a graduated scale 19, the number of graduations corresponding to the number of teeth of the ratchet wheel.

Each time the piston rod is elevated to its fullest extent, the block strikes against the shoulder 16 of the pawl, and raises the latter, 40 so that the pawl may engage with a fresh tooth of the ratchet wheel, and then as the piston rod descends the block will leave the shoulder of the pawl, and the latter will rotate the ratchet wheel to the extent of a 45 single tooth, this movement being indicated on the scale 19.

In order to accurately control the quantity of liquid delivered, a stop rod 6 is mounted in suitable bearings projecting from the 50 casing, one of these bearings being in the form of a disk 11, and the other in the form of a bracket 8. This rod is provided with a handled catch 12 which may be arranged to engage with a number of locking notches 55 13 formed at the top of the disk, and by turning the rod to a greater or less extent, one or other of a number of stop blocks 9—10 may be moved into the path of the block 7 in order to limit the extent of downward 60 movement of the latter, so that the block will travel downward far enough to deliver a predetermined quantity of liquid from the

cylinder, and will be positively stopped when this quantity has been delivered. The position of the blocks may be such as to 65 indicate either quarts, gallons or other units of liquid measurement.

At the delivery end of the pipe 32 is an elbow 33. The lower face of this elbow has a horizontal flange or shoulder 36 and below 70 this shoulder the outer wall of the nozzle is provided with an annular recess 35 over which is placed a tapered nozzle 34. This forms an air chamber which will prevent, or to a material extent reduce the loss of 75 liquid by dripping.

I claim:

1. In a measuring pump, a pumping mechanism including a piston rod, means for actuating the same, a block secured to the piston rod and adjustable in the direction of the length of the rod, an adjustable stop for engaging said block, an indicating device including a ratchet wheel, a pointer carried thereby, a graduated dial over which the pointer may travel, a pawl engaging the ratchet wheel, said pawl having a shoulder disposed in the path of movement of the block, and means for retracting the pawl.

2. In a measuring pump, a pumping mechanism including a piston rod, means for operating the rod, a block secured to the rod, an indicator with which the block engages, and an adjustable means for limiting the movement of the rod during the discharging operation of the pump.

3. A measuring pump including a piston rod, an indicating device, a block carried by the piston rod, and operating said indicating device, and adjustable stops movable into 100 the path of the block and serving to limit the discharging movement of the pump.

4. A measuring pump including a piston rod, means for operating the rod, a block projecting from said piston rod, a revolvably 105 mounted stop rod having a plurality of blocks, any one of which may be adjusted in the path of movement of the piston rod block, a stop disk having a series of notches, and an operating handle carried by the stop 110 rod and having a catch arranged to engage any one of said notches.

5. A measuring pump including a piston rod, a block carried thereby and having a pointer, a graduated scale over which the pointer may travel, a link belt secured to the block, and means for actuating said link belt.

Substantially as herein set forth.

CHARLES S. JONES.
